DESIGN FOR A PIANO

George W. Cushing, Newark, N. J., and Arthur Hahn, New York, N. Y., assignors to Krakauer Bros., New York, N. Y., a corporation of New York

Application January 30, 1948, Serial No. 144,144

Term of patent 14 years

(Cl. D56—9)

To all whom it may concern:

Be it known that we, George W. Cushing, a citizen of the United States, residing at 37 Monticello Avenue, Newark, Essex County, State of New Jersey, and Arthur Hahn, a citizen of the United States, residing at 10 West 86th Street, New York, county of New York, and State of New York, have invented a new, original, and ornamental Design for a Piano, of which the following is a specification, reference being had to the accompanying drawings, forming a part thereof.

Figure 1 is a front perspective view of the piano in the playing position;

Figure 2 is a rear elevation of the piano with the lid in the lowered position;

Figure 3 is a top plan view of the piano in the position of Figure 2;

Figure 4 is a left end elevation of the piano in the position of Figure 2;

Figure 5 is a rear perspective view of the piano in the vertical position;

Figure 6 is a right end perspective view of the piano in the position shown in Figure 5;

Figure 7 is a top plan view of the piano in the position shown in Figure 5; and

Figure 8 is a rear elevation of the piano in the position shown in Figure 5.

We claim:

The ornamental design for a piano, as shown and described.

GEORGE W. CUSHING.
ARTHUR HAHN.
